Primary Examiner — Martie K Holtje(74) *Attorney, Agent, or Firm* — Wilson Sonsini Goodrich & Rosati(57) **CLAIM**

The ornamental design for a radar enhanced parking meter, as shown and described.

DESCRIPTION

FIG. 1 is a front perspective view of a radar enhanced parking meter, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a rear perspective view thereof.

The structure depicted by broken lines in the drawing has been shown for the purpose of illustrating environment that forms no part of the claimed design.
